UNITED STATES PATENT OFFICE.

FRANK M. HURLEY, OF BENNINGTON, OHIO.

MUSIC-LEAF TURNER.

SPECIFICATION forming part of Letters Patent No. 451,763, dated May 5, 1891.

Application filed January 6, 1891. Serial No. 376,891. (No model.)

To all whom it may concern:

Be it known that I, FRANK M. HURLEY, of Bennington, in the county of Morrow and State of Ohio, have invented certain new and useful Improvements in Music-Leaf Turners; and I do hereby declare the following to be a full, clear, and exact description of the invention, such as will enable others skilled in the art to which it pertains to make and use it, reference being had to the accompanying drawings, which form part of this specification.

My invention relates to an improvement in music-leaf turners; and it consists in, first, the combination of a suitable number of bent rods which carry adjustable clamps at their upper ends and toothed wheels at their lower ones, and a corresponding number of toothed push-rods, by means of which the bent rods are made to turn the leaves, and, second, the combination of two vertically-adjustable rods, an adjustable frame placed thereon, and a spring-actuated, endwise-moving, and partially-rotating rod provided with devices for catching over the upper ends of the leaves, as will be more fully described hereinafter.

The object of my invention is to produce a music-leaf turner by means of which the music can be quickly and readily turned without the performer having to stop an appreciable length of time in playing to turn them.

Figure 1 is a front elevation of a leaf-turner which embodies my invention. Fig. 2 is a plan view of the same, the upper portion of the rods for turning the leaves being removed. Fig. 3 is an end view.

A represents the base-piece, from the top of which rises the board B, which is cut away at the center of its top edge, as shown, so as to receive the frame C, which is placed upon the two vertically-adjustable rods D, which are inserted in holes made in the top edge of the board B. These rods can be raised and lowered at will, so as to enable the frame C to be adjusted according to the height of the music or book being used. Journaled in this frame C is an endwise-moving partially-turning rod H, to which the spring I is applied for causing the rod to partially revolve whenever it is left free to move. Projecting from the rod are the two arms J, which catch over the upper edges of the two outer leaves or

the covers and those leaves which are not to be brought into use. In order to hold these arms in a raised position when not in use, one end of the rod has a shoulder K formed upon it, and this shoulder catches under a corresponding shoulder or flange L upon one end of the frame C. As soon as the rod is moved endwise by means of its handle N against the pressure of the spring the shoulder upon the end of the rod is moved from under the shoulder upon the frame, and then the spring exerts its tension in turning the rod so as to turn the arms down over the top of the outer pages or back of the music.

In order to hold the frame C at any desired position upon the two vertical rods, a spring O is secured to the top of the frame, and the ends of this spring bear against the rods, so as to exert a frictional contact thereon.

Secured to opposite ends of the base A are the two spring-wires P, which catch against the lower edges of the outer sheets, the back, or the leaves that are not to be brought into use. Rising from the top of this base A are the two pins Q, behind which these wires are made to catch when they are not to be brought into use.

Extending from the front of and through a portion of the base A are a number of push-rods R, which are provided with suitable buttons or handles at their outer ends, and which have cogs or teeth formed upon one side of their inner ends for the purpose of operating the small toothed wheels S, placed upon the lower ends of the rods T, for turning the sheets of music. Only one of the push-rods is made straight, while each one of the others is bent so as to bring all of their inner ends in a vertical line with each other. The wheels and the bent portions of the push-rods are placed in a recess formed in the top of the rear edge of the base A, and the wheels are placed one above the other, so that one rod will not interfere with the other as it is brought into use. The operating-rods extend upward from their wheels through a suitable bearing U, and have their upper ends bent at right angles, so as to receive the adjustable rods V, which are passed through them, and which rods have their clamps W secured to their lower ends for catching hold of the upper edges of the sheets of music. When the

push-rods are successively pulled out, they turn the sheets of music connected to them and more quickly and readily than could be done if the operator were to use his or her hands.

Having thus described my invention, I claim—

1. The combination of the vertical board, the vertically-adjustable rods placed therein, the adjustable frame placed upon the rods, the spring-actuated endwise-moving partially-turning rod provided with arms, and a shoulder at one end to engage with a corresponding shoulder upon the frame, substantially as shown.
2. The combination of the base, the board B, which rises therefrom, the vertically-adjustable rods placed in recesses in the board, the vertically-adjustable frame placed upon

the rods, a spring secured to the frame and bearing against the rods, and a spring-actuated, endwise-moving, and partially-revolving rod provided with arms, substantially as described.

3. The combination of the push-rods having their inner ends provided with teeth, with the wheels placed one above the other, the bent operating-rods, to the lower ends of which the wheels are secured, and the rods provided with clamps, and which are vertically adjustable upon the operating-rods, substantially as set forth.

In testimony whereof I affix my signature in presence of two witnesses.

FRANK M. HURLEY.
